UNITED STATES PATENT OFFICE

ALEXANDER BRUNO PREUSS, OF BERLIN, GERMANY, ASSIGNOR TO SIEMENS & HALSKE AKTIENGESELLSCHAFT, OF SIEMENSSTADT, NEAR BERLIN, GERMANY

TELEPHONE SYSTEM

Application filed April 15, 1931, Serial No. 530,322, and in Germany August 26, 1930.

The present invention relates to a circuit arrangement for preselectors in telephone systems in which preselectors in special cases are set in a particular position.

5 This might be the case when all the preselector's outgoing lines are engaged or when the switching operations required for the further setting up of the connection after the initiation of a call over a subscriber's line 10 have not been initiated within a specified time.

The object of the invention is to achieve in a simple manner that a subscriber whose preselector is set in a special position can be 15 called. This is achieved by a test circuit, made possible by the free hunting of the final selector, being set up at the setting of the preselector in a special position.

An embodiment of the invention is shown 20 in the drawing to which embodiment, however, the invention is not limited.

A preselector is shown in the drawing with which is associated a line relay and a test relay. It is obvious that the arrangement 25 according to the invention can also be used for preselectors with a single relay designed as a two-step relay or relay with double armature.

When the subscriber at the station T_n lifts 30 his receiver the following circuit is set up: earth, winding I of the repeater device supplying the busy signal, contact $4t$, line L_b , line loop at the subscriber's station T_n , line L_a , contact $3t$, relay R , battery, earth. Relay R is energized and actuates contact $1r$. 35 Hereby the following circuit for the rotary magnet D of the preselector is completed: earth, interrupter U , rotary magnet D , contact $2t$ thrown-over contact $1r$, position C of the switch wiper f of the preselector, battery, earth. The rotary magnet is operated 40 in this circuit and the switch wipers of the preselector are advanced step by step. When the preselector has left the position O the forward stepping circuit is maintained over 45 the contact segment $1-10$ of the switch wiper f . If a free line has been found, by way of example the line L_c 1, the following circuit is completed: earth, not shown switch- 50 ing device, winding II of relay P , contact

$5p$, contact th of a not shown time switch, line L_c 1, wiper c of the preselector, windings I and II of relay T , switch wiper e of the preselector, contact $1r$, segment $1-10$ of the switch wiper f , switch wiper f , battery earth. In this circuit the relays P and T are energized whereby contacts $2t$, $3t$, and $4t$ are actuated. The forward stepping circuit for the rotary magnet is broken by contact $2t$ whereby the preselector is brought to rest. 55 By the throwing over of contact $2t$ battery is immediately applied to winding I of relay T , with the result that winding II is disconnected, whereby a guarding is effected in known manner. Contacts $3t$ and $4t$ switch through the subscriber's line. Relay P actuates its contacts $5p$. If the connection is not completed due to the subscriber not having dialed within a certain period contact th is opened in known manner, whereby the test circuit is broken. Relays P and T release. 60 On the release of relay T relay R is re-energized as the line loop at the subscriber's station would not yet be open. Contact $1r$ is thrown over. Further, contact $2t$ is brought to its original position whereby the following forward stepping circuit is established: earth, interrupter U , rotary magnet D , contact $2t$, segment $1-10$ of the switch wiper f , battery, earth. The preselector operates and is able to set itself to the next 65 free line. When this has taken place in the already described manner the preselector, in case the subscriber still maintains the line loop, is advanced to the next free line after a certain period in the already described manner by the opening of contact th . This advance continues until the switch wipers of the preselector have reached position 11 . When this position is reached the forward 70 stepping circuit is broken at switch wiper f of the preselector. 75

Relay T is not energized in this position. By the contacts $3t$ and $4t$ having taken up the positions shown in the drawing, the subscriber receives the busy signal over winding I of the busy signal device. If now the subscriber is called at the subscriber's station T_n , that is to say, if test voltage is applied to the line L_c over a final selector the 80 85 90 95

circuit extends as follows: not shown device in final selector, line L_c , contact 0 in the contact bank of the switch wiper c of the pre-selector, contact 11 in the same contact bank, 5 switch wiper c , windings I and II of relay T of the preselector, switch wiper e in position 11, battery, earth. Relay T is energized in this circuit and actuates contacts 2 t , 3 t , and 4 t . By the throwing over of contacts 3 t 10 and 4 t the busy signal device is disconnected. By the throwing over of contact 2 t no further switch procedures are caused. Only at the release of the connection, that is to say, after the circuit over the line loop and also the circuit 15 for relay T has been broken, can the pre-selector reach its original position as, by the throwing over of contacts 1 r and 2 t into their normal positions, the forward stepping circuit is again established in order to bring the 20 preselector into its original position.

Similar switching operations are effected when all outgoing lines are engaged at a call. In such a case the preselector arrives immediately into position 11 in which it will 25 be brought to rest and in which also a call is possible in the already described manner. It should also be mentioned that relays R and T in the above described circuit could be replaced by a single relay, for example, a 30 two-step relay in which the contact 1 r would be actuated at the energization of winding R, while contacts 2 t , 3 t , and 4 t would be actuated at the energization of winding T.

What is claimed is:

1. In a telephone system, a subscriber's line terminating in a lineswitch, means responsive to an abnormal condition on said line for operating said switch to a particular position to prevent its connection to other switching apparatus, and means for rendering said line available for incoming calls while said switch is in said position. 100
2. In a telephone system, a subscriber's line terminating in a lineswitch, means responsive to an abnormal condition on said line for operating said switch to a particular position, and a test circuit set up by said switch in said position to allow the associated line to be called. 105
3. In a telephone system, a subscriber's line terminating in a lineswitch, means responsive to an abnormal condition on said line for operating said switch to a particular position, and a test circuit prepared by said switch in said position to make the line available for incoming calls, said test circuit including the test wiper of said switch and the normal and special position bank contacts of said test wiper. 110
4. In a telephone system, a subscriber's line terminating in a lineswitch having a normal position, a test circuit prepared over a test wiper of said switch and its normal bank contact for establishing incoming calls to said line, means for operating said switch to a 115
- 65

special position responsive to an abnormal condition on said line, and a test circuit prepared over said test wiper and its special position bank contact to render said line available to incoming calls when said switch is in 70 said special position.

5. In a telephone system, a subscriber's line terminating in a lineswitch, means responsive to an abnormal condition on said line for operating said lineswitch to a special position to prevent its connection to other switching apparatus, means for rendering said line available to incoming calls while said condition exists, and means for applying busy tone to said line while said switch is in said special position and the line is not being called. 75

6. In a telephone system, a subscriber's line terminating in a lineswitch, means responsive to an abnormal condition on said line for operating said lineswitch to a special position to prevent its connection to other switching apparatus, and for applying busy tone to said line, a test circuit prepared by said switch in said special position to make the line available to incoming calls, and means in said test circuit for removing said busy tone when an incoming call is received. 80

In witness whereof, I hereunto subscribe my name this 25th day of March, A. D. 1931.
